UNITED STATES PATENT OFFICE.

JOHN CARTER AND ALFRED GEORGE CARTER, OF MALDEN,
MASSACHUSETTS.

MUFFLE.

SPECIFICATION forming part of Letters Patent No. 752,438, dated February 16, 1904.

Application filed July 28, 1903. Serial No. 167,291. (No model.)

To all whom it may concern:

Be it known that we, JOHN CARTER and ALFRED GEORGE CARTER, citizens of the United States, and residents of Malden, in the county 5 of Middlesex and State of Massachusetts, have invented a new and Improved Muffle, of which the following is a full, clear, and exact description.

Our invention relates to muffles, and more 10 particularly to a type of muffle in which combustion is very thorough and the heat evenly distributed.

Reference is to be had to the accompanying 15 drawings, forming a part of this specification, in which similar characters of reference indicate corresponding parts in both figures.

Figure 1 is a vertical central section on the line 1 1 in Fig. 2 through a muffle embodying 20 our invention, and Fig. 2 is a section upon the line 2 2 in Fig. 1.

A base 1 is provided with an annular portion 2, surrounded by a cylindrical portion 3, and upon this cylindrical portion is a conical stack 4. Fire-holes are shown at 5, each being 25 provided with grate-bars 6 and with a door 7, having a threshold 8, supported upon a lintel 9. Above the grate-bars 6 are apertures 10, from which the smoke and gases of combustion are free to pass upward through passages 30 11 to the chamber 12. A central flue 13 is provided, and encircling this central flue is a relatively large cylinder 14, surmounted by a dome 14^a, this dome being connected with the central flue 13. The lower end of the central flue 13 is 35 connected with a head 13^a, below which are radially-disposed passages 15, each of which is connected with a vertical passage 16. Each vertical passage is obstructed at its upper portion by an arch 17. A dome 18 is supported by 40 the arches 17, which obstruct the passages 16, and by apertured arches 17^a, which register with the passages 11. By means of passages 19 the vertical passages 16 are free to discharge 45 the gases of combustion into the conical stack 4. A plate 20^a in the nature of a damper projects slightly from the junction between the cylinder 3 and the stack 4, said plate being slidably movable back and forth over the passages 19, as desired. A comparatively short alternative

flue 21 is mounted upon the dome 18, and a 50 cap 22, provided with a ring 23, is pivoted at 24 upon the alternative flue 21 and is free to move upwardly, as indicated by dotted lines in Fig. 1, a chain 25^a being connected with the ring 23 and passing over a pulley 26 to a handle 27, whereby the cap may be opened when starting the fires, and when the fires have attained sufficient headway the cap may be closed. A passage 28 is provided in the cylindrical portion 3 for the purpose of inspecting 55 the condition of the flames within the passages 11, and it will be noted that the passages 11 and 16 alternate with each other.

The muffle-chamber is shown at 25. Passages 29 in the annular portion 2 are bifurcated into distinct branches 15^a 15^b, (see Fig. 2,) and these branches terminate in apertures 15^c (see Fig. 1) for the purpose of discharging air into the flame, such air being heated in its passage from passages 29 to the apertures 15^c 60 and does not in any measure cool the fires, but mixing with the gases adds to the intensity of the same.

Our invention is used as follows: Fires being lighted in the several fire-holes 5 by means 65 of fuel resting upon the grate-bars 6, the smoke and gases of combustion pass upwardly through all of the passages 11, thence through the passages 12, and downward through the central flue 13, as indicated by the arrows in 70 Fig. 1. The smoke and gases arriving at the bottom of the central flue 13 radiate outwardly and pass upwardly through the passages 16 until they encounter the deflecting-arches 17, from whence they pass upwardly through the 75 passages 19 20 into the conical stack or chimney 4, thus making their escape. It will be noted that the several upward drafts represented by the passages 11 are arranged alternately with the several upward drafts represented by the passages 16. The air is drawn 80 inward through the several radially-disposed passages 29 and is thence divided and distributed through the branches 15^a 15^b and apertures 15^c to the flames at points elevated somewhat above the grate-bars 6. By this means 85 the device acts somewhat in the capacity of a smoke-consumer, thereby causing thorough 90 95

combustion of the unburned gases and smoke and not only economizing fuel, but causing a more perfect distribution of the heat.

Having thus described our invention, we 5 claim as new and desire to secure by Letters Patent—

1. In a muffle, the combination of a hollow member, a cylinder mounted therein and connected thereto, a central flue connected with 10 said cylinder and passing through the same, a dome covering said cylinder and said flue, said dome being provided with an aperture, a member for closing said aperture, and mechanism connected with said member and extending 15 without said hollow member for the purpose of enabling the same to be operated from a point external to the muffle.
2. In a muffle, the combination of a hollow

member, a revoluble pulley mounted therein, a central flue disposed within said hollow member, a cylinder encircling said flue, a dome covering said cylinder and said central flue, said dome being provided with an aperture, a closure member for closing said aperture, and a chain connected with said closure member and 20 passing over said pulley for the purpose of enabling said closure member to be operated from a point external to the muffle.

In testimony whereof we have signed our names to this specification in the presence of 25 two subscribing witnesses.

JOHN CARTER.
